United States Patent

Des. 237,110
Patented Oct. 7, 1975

237,110

FONT OF SYSTEM-SERIES LOGOTYPES

N. Dominic Marucci, Philadelphia, Pa., assignor to Burroughs Corporation, Detroit, Mich.

Filed Apr. 10, 1973, Ser. No. 349,713

Term of patent 14 years

Int. Cl. D18—03

U.S. Cl. D64—12 B

The single figure is a face view of a font of system-series logotypes showing my new design.

I claim:

The ornamental design for a font of system-series logotypes, substantially as shown and described.
